United States Patent Office.

E. A. G. ROULSTONE, OF ROXBURY, MASSACHUSETTS.

Letters Patent No. 63,178, dated March 26, 1867.

IMPROVEMENT IN CARPET-BAGS.

The Schedule referred to in these Letters Patent and making part of the same.

TO ALL WHOM IT MAY CONCERN:

Be it known that I, E. A. G. ROULSTONE, of Roxbury, in the county of Norfolk, and State of Massachusetts, have invented an Improvement in Travelling-Bags; and I do hereby declare that the following, taken in connection with the drawings which accompany and form part of this specification, is a description of my invention sufficient to enable those skilled in the art to practise it.

In the manufacture of travelling-bags it is very desirable to have a strong and rigid frame to which to apply the flexible bag material, and to have, in connection with such frame, some simple and efficient means of securing firmly and enduringly thereto the cloth or other flexible bag-forming material. It is to such construction of the frame, and in provision for securing thereto the cloth or leather, that this invention relates, and my present improvement consists in combining with corners formed by cutting or slitting and lapping the plate and riveting together the overlapping parts, a hollow rigidifying bead at the angle of the frame and extending throughout its length; also in securing the leather or cloth to the edge of the frame by folding the edge over the edge of the frame and securing it thereto by a folded metal strip, pressed over the folded edge of cloth or leather, and the edge of the frame, and secured thereto by rivets, spurs, or stitches passing through the three.

The drawings represent a frame embodying the invention—

A showing a side view of the frame, and B a cross-section of the same, with the flexible bag-forming material applied thereto. *a* denotes the metal plate forming the frame, the edges being bent to stand right angularly, forming the mouth-piece or jaw *b*, and the body-applying edge *c*, and the ends of the plate being also turned to form the end pieces of the frame. In turning these end pieces the metal in the part *c*, at the points where the corners are to be made, is cut out or displaced so as to enable the metal to bend freely, and to make a joint of neat and finished appearance. As the cutting of the metal, however, weakens the corner *d* to some extent, and as it is desirable to strengthen the frame all along the angle made by the parts *b* and *c* of the frame, I form a raised hollow bead, *e*, at the angle of the frame, extending the same around the corners, along the end and top pieces, as seen at A, thereby imparting great strength and rigidity to the frame, and by raising the bead *e* above the surfaces *b c* I protect the said surfaces from abrasion and wear. The flexible leather or body is seen at *f*, it being formed either with or without a lining, as may be desirable. In applying the cloth or leather to the frame its edge is first doubled over the edge of *c*, and over this, and so as to hold the leather or cloth to both the outer and inner surfaces of the edge *c* is applied a folded metal strip, *g*, as seen at B, a row of rivets, *h*, or stitches, securing the whole together, after application of which the leather is turned over, as seen at B, entirely concealing the strip *g* and the other means of connection, and causing the strain upon the bag material to be chiefly borne along the outer edge of the strip, instead of by the rivets, as would be the case if the rivets alone were used.

I claim, in combination with the corners *d*, made by lapping the metal, the bead *e*, extending around these corners and along the angle of the frame, substantially as set forth.

Also, the manner of applying the flexible bag-forming material to the frame, by means of the metal strip *g*, folded over the folded edge of the cloth or leather and the edge of the frame, and secured to the frame by rivets or other fastening devices, substantially as set forth.

E. A. G. ROULSTONE.
